UNITED STATES PATENT OFFICE.

FREDERICK R. KEITH, OF RANDOLPH, MASSACHUSETTS.

INSOLE.

1,211,168.

Specification of Letters Patent. Patented Jan. 2, 1917.

Application filed May 15, 1916. Serial No. 97,504.

To all whom it may concern:

Be it known that I, FREDERICK R. KEITH, a citizen of the United States, residing at Randolph, county of Norfolk, State of Massachusetts, have invented an Improvement in Insoles, of which the following description, in connection with the accompanying drawing, is a specification, like characters on the drawing representing like parts.

This invention relates to insoles such as are used in the manufacture of welt boots and shoes, and the object of the invention is to provide a novel insole which can be inexpensively manufactured but which has all the essential characteristics necessary to an insole.

My improved insole comprises a body element which is made thinner at its edges thereby to provide a shoulder which extends parallel to but is situated at a slight distance back from the edge, and a rib-forming element which is positioned by said shoulder and is secured to the thinner edge portion of the body element.

In order to give an understanding of my invention I have illustrated in the drawings some selected embodiments thereof which will now be described, after which the novel features will be pointed out in the appended claims.

Figure 1 is a plan view of an insole embodying my invention; Fig. 2 is an enlarged section in perspective on the line 2—2, Fig. 1; Fig. 3 is a similar view showing a different embodiment of the invention; Fig. 4 is a similar view showing a still different embodiment of the invention; Fig. 5 is a view of the rib-bearing strip before the rib is formed thereby.

1 designates the body element of the insole which may be made of any suitable material having sufficient strength for the purpose. A comparatively-cheap material, such as leather-board, can be successfully used. This body element 1 is reduced in thickness at its edge 2 and is formed with a shoulder 3 which extends parallel to the edge. A rib-forming element is secured to the thin edge portion 2 of the body element and is positioned by the shoulder 3. This rib-forming element may be made in various ways without departing from the invention.

In Figs. 1 and 2 I have shown it as formed from a strip 4 of leather or other suitable material, such as shown in Fig. 5, said strip being of a width equal to the

width of the thin edge portion 2. This strip is channeled at its opposite sides, as shown at 6 and 7 in Fig. 5, and the portions 8 and 9 are turned up to produce the rib that receives the inseam stitches. This rib-forming element 4 may be secured to the body element 1 in any suitable way. I will preferably sew it thereto by two lines of stitches 10 and 11 which are sewed through the portions 12 and 13 thereof. Any suitable material may be used for the rib-forming element 4, but I will preferably use a material which is sufficiently tough and strong so that the rib which is formed by the upturned lips 8 and 9 will be strong enough to hold the inseam stitches during the manufacture of the shoe. With an insole made in this way the body portion 1 may be made from comparatively inexpensive material.

In Fig. 3 I have illustrated a different embodiment of the invention wherein the rib-forming element 40 is channeled from the outer edge only and the rib is formed by turning up a single lip 80. In this embodiment of the invention the face of the insole is covered by a layer 14 of canvas or other fabric which overlies the upturned lip 80 and with the latter forms the complete inseam-receiving rib 15. In this embodiment, the strength of the fabric 14 augments the strength of the single lip 80 and thus a sufficiently strong inseam-receiving rib may be produced.

In Fig. 4 a still different embodiment of the invention is shown wherein the rib-forming element is formed by a strip 16 of fabric which is folded longitudinally and is sewed to the thin edge portion 2 of the body element 1 by stitches 18, said folded fabric being sewed closely adjacent the shoulder 3 and the latter serving as a guiding or positioning means for the member 16. In this embodiment of the invention too I have shown the insole as covered with a layer 14 of canvas or other fabric which overlies the rib-forming strip 16 and with the latter forms the complete inseam-receiving rib 19.

In all of the embodiments of the invention the rib-forming element is sewed to the thin edge portion 2 of the body element and is positioned by the shoulder 3. This shoulder 3 acts as a guide to properly position the rib-forming element during the process of sewing it to the body element 1.

In the embodiment shown in Fig. 2 the

channel 7 is so formed that the portion 13 of the strip 4 has a thickness equal to the depth of the shoulder 3 so that when the rib-forming element is sewed to the 5 insole the top surface of the portion 13 will be flush with the face of the insole. The channel 6 is so formed that the portion 12 is thinner than the portion 13. In sewing the welt and upper to the insole the curved 10 needle which is usually used in sewing machines for this purpose enters the rib at the base thereof from the inner side. By having the insole thinner on the outer side of the rib, the needle will emerge from the 15 rib on the outer side thereof above the top of the insole. This same feature is also present in the embodiment shown in Figs. 3 and 4, for in each of these constructions the completed insole is thinner outside of the 20 inseam-receiving rib than it is on the inside thereof.

It will be observed that in all of the illustrated embodiments of my invention the outwardly-facing shoulder 3 is situated 25 entirely between the top and bottom faces of the body member and that no part of the body member is employed in making the inseam-receiving rib, all of said rib being formed by material which is separate from 30 but secured to the body member.

An insole embodying my invention can be manufactured very cheaply because relatively-cheap material can be used, for the body element 1.

35 In the embodiment shown in Figs. 2 and 3 I will preferably make the rib-bearing

element of leather, but the invention is not confined to the use of leather for this purpose.

I claim:

1. An insole comprising a body element having an outwardly-facing rib-positioning shoulder formed on an integral part thereof adjacent its edge, the portion of said body element between the shoulder and the 45 edge being thinner than the rest thereof and said shoulder having a depth equal to the difference in thickness between the main portion of the body element and the thin edge thereof, and a rib-forming element secured to the thin edge portion of the body element and positioned by the shoulder, said rib-forming element providing an inseam-receiving rib which is made entirely from material that is separate from but 50 secured to the body element.

2. An insole comprising a body element formed with an outwardly-facing shoulder adjacent its edge and having the edge portion between the shoulder and the edge 60 thinner than the rest thereof, and a rib-forming element secured to said thinner edge portion of the body element and positioned by the shoulder thereof, said rib-forming element being channeled longitudinally from the outer edge and the channeled portion being turned up to form an inseam-receiving rib.

In testimony whereof, I have signed my name to this specification.

FREDERICK R. KEITH.
